United States Patent Office

Des. 178,103
Patented June 19, 1956

178,103

ASH TRAY

Eric Wedemeyer, Floral Park, N. Y., assignor to Hamilton Art Metal Corporation, New York, N. Y., a corporation of New York

Application November 16, 1955, Serial No. 38,924

Term of patent 14 years

(Cl. D85—2)

Fig. 1 is a perspective view of an ash tray, showing my new design;

Fig. 2 is a side view thereof; and

Fig. 3 is a top plan view thereof.

The dominant features of my new design are shown in full lines in the drawing.

I claim:

The ornamental design for an ash tray, substantially as shown and described.
